M. Randolph & Co.

United States Patent Office.

WILLIAM C. SMITH, OF WARRENSBURG, MISSOURI.

Letters Patent No. 77,668, dated May 5, 1868.

IMPROVED SUGAR-EVAPORATOR.

The Schedule referred to in these Letters Patent and making part of the same.

TO ALL WHOM IT MAY CONCERN:

Be it known that I, WILLIAM C. SMITH, of Warrensburg, in the county of Johnson, and State of Missouri, have made certain new and useful Improvements in Sugar-Evaporators; and I do hereby declare that the following is a full and clear description thereof, reference being had to the accompanying drawings, and to the letters of reference marked thereon.

This invention relates to a certain arrangement of the fire-box, air-ducts, flues, and dampers, whereby the heat generated within the said furnace is held more absolutely under the control of the operator, and rendered perfectly adapted to the purpose of reducing saccharine sirups when placed within the superimposed evaporating-pans. More particularly, this is an improvement in an evaporating-apparatus secured to the inventor of this improvement, by Patent No. 65,702, dated June 11, 1867.

To enable those skilled in the art to make and use my improved apparatus, I will proceed to describe its construction and operation. Of the accompanying drawings—

Figure 1, sheet 1, is an elevation in perspective of the improved apparatus.

Figure 2, sheet 1, is a central sectional elevation of the same.

Figure 3, sheet 1, is a transverse sectional elevation, taken through the fire-box and smoke-stack.

Figure 4, sheet 2, is a sectional plan, taken on the line $x'y'$ in fig. 2.

Figure 5, sheet 2, is a sectional plan, taken on the line $x'y'$ in fig. 2.

A represents the shell of the device, and may be constructed in a portable manner by mounting it on wheels, or it may be made stationary and enclosed in a setting of masonry. The general contour of this shell A is very similar to that of the corresponding device in Patent No. 65,702, and, like it, the present device has three pan-seats, $a^1 a^2$, arranged like a flight of steps. On the upper one of these steps a^1 , the primary pan is placed; on the second and next lower one, a^1 , is located the evaporating-pan; and on the lowest, a^2 , is placed the finishing-pan. The pans themselves are not illustrated in the accompanying drawings, as they form no part of the invention, the sole end and aim of which are to so arrange and control the heat as to render it entirely subservient to the purpose of reducing the sirup placed within the aforesaid pans. The fire-box B may be constructed of cast-iron plates, and provided with a grate, b, for the support of the fuel. For convenience sake, the door b¹, through which the furnace is to be fed with fuel, should be located at the back end of the apparatus. By means of the walls A', the back end of the shell or case A is divided into three compartments, B B' B², the central one of which, B, is the fire-box. The air which feeds the fire is to be admitted, through the door b², into the chamber B¹, and thence it finds its way around through sinuous passages, in the direction of the arrows b³, into the chamber B², where it escapes through the aperture b⁴, into the fire-box below the grate-bars. There are retaining-walls b⁵ in the chambers B¹ B², for the purpose of retarding the passage of the air through them until it is thoroughly heated, and heating the air supplied to the furnace is the object of this arrangement of the said chambers and passages. In case the draught thus provided should not prove sufficient in starting the fire, the small door, b⁶, may be opened in the front, or the door v leading to the ash-pit B³. Directly over the furnace there is a damper or slide, D, which may be opened, so as to permit a direct communication from the furnace to the chimney C. The damper or slide D is placed in the horizontal partition-wall d, which forms the top of the fire-box, and another slide, D¹, is placed in the same partition, forward of the slide D, as is shown in figs. 2 and 4. The wall d extends the entire length of the machine, parallel with the pan-seats $a^1 a^2$, and between the said pan-seats and the aforesaid wall d, the hot-air and smoke-flues are arranged by means of the said walls, and the vertical partitions E E, and the dampers e e' and e' e', the same as in my former patent. In front of the damper or slide D¹ is another, D², operated by the rod d'. As has been already described, the opening of the damper D admits the current of smoke and hot gases directly to the chimney C. In like manner the opening of the damper D¹ admits said heated current to the bottom of the first pan, and the opening of the damper D² admits the heat to the bottom of the second pan. The dampers e e' are used for the same purpose and in the same manner in which they were in my former patent.

Having described my invention, what I claim, is—

1. The air-heating chambers $B^1 B^2$, when combined with the fire-box B , in the manner and for the purpose herein set forth and described.
2. I claim the dampers or slides $D D^1 D^2$, when arranged and operated as and for the purpose shown and described.

WM. C. SMITH.
